ATTORNEY.

UNITED STATES PATENT OFFICE

GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

SEPARABLE FASTENER

Original application filed September 22, 1926, Serial No. 137,018, and in Great Britain September 22, 1927.
Divided and this application filed November 11, 1929. Serial No. 406,280.

This invention relates to separable fastener stringers particularly of the type adapted for sliderless operation and the present application is a division of my co-pending application Ser. No. 137,018 filed September 22, 1926, Patent No. 1,746,565, granted February 11, 1930.

An object of the present invention is to provide an improved construction of the interlocking members for a type of multiple fastener adapted for sliderless operation.

Another object is to provide an improved construction of the interlocking members in a fastener of this type wherein a member on one stringer is arranged directly opposite a member on the other stringer to form an interlocking pair.

A more specific object of my invention is to provide an improved construction of the interlocking members so that they may be manufactured very easily from sheet metal. Other objects and advantages of my invention will appear more fully during the course of the following specification.

In the accompanying drawings, I have shown for purposes of illustration two embodiments which my invention may assume in practice. In these drawings;

Figure 1 is a plan view of the fastener of my invention being closed by the thumb and finger of an operator.

Fig. 2 is a transverse sectional view of the fastener stringers.

Fig. 3 is a section extending longitudinally of the stringers through a pair of locking members in interlocked relation.

Fig. 4 is a similar view of the members as they are approaching interlocked relation.

Figure 5 is a perspective view illustrating the faces of the interlocking members and showing a slightly modified stringer construction.

Figure 6 is a transverse section similar to Figure 2 but showing the modified stringer construction of Figure 5.

The separable fastener illustrated comprises a pair of flexible stringers 6 and 7 adapted to be attached to the edges of a gap to be closed. A fastener of this type is particularly adapted for handbags, pouches and

similar articles where there are two flexible overlapping members to be connected together. A series of interlocking elements 8 is arranged on the inner face of each stringer in position to interlock with a series of similar elements 9 on the other stringer. In Figure 2, the material of the article is indicated at 10 and 11 and it will be noted that the material extends over the interlocking elements so that there is no exposed metal.

Each of the interlocking elements is preferably made from a flat piece of metal cut to proper length and bent inwardly at opposite ends as indicated at 12 and 13 to provide clamping means for connecting the locking member to its flexible stringers. In Figure 2 the edges of the material 10 and 11 are folded over as shown at 14 and 15 to extend under the inwardly bent portions 12 to provide a secure connection between the outer ends of the locking members and the material of the stringers. At the other end of the locking members, there are provided a pair of strips 16 and 17 which are attached at one edge to the material 10 and 11 respectively and which have their other edges doubled over and turned under the ends 13 of the locking members. The body portions of the locking members arranged between the bent ends are preferably bent inwardly so as to lie closely against and parallel with the body portion of the opposite member.

An interlocking tongue 18 is cut out and bent up at an acute angle from each of the locking members and a recess 19 is formed in each member adjacent such projection to provide means for receiving the projection on an opposite locking member. As best shown in Figure 3, the locking tongues are flattened out at their ends as indicated at 20 by a suitable pressing operation so that the tongues are longer than the recesses 19. If desired, of course, instead of flattening out the tongues in the manner described, the recesses 19 may be made somewhat shorter than the locking tongues. The edges of each of the recesses provide suitable shoulders 21 for interlocking engagement with the ends of the tongues 18 whereby the fastener is securely held together.

100

In the modification shown in Figures 5 and 6 the sides 22 and 23 of a pocketbook, handbag or similar article, have their edges turned over at 24 and 25 respectively to form connections with the inner ends of the locking members. A pair of strips of material 26 and 27 are attached to the sides 22 and 23, respectively. These strips cover the locking members of the fastener and have their ends 28 and 29 doubled over to connect with the outer ends of the locking members.

In both forms of stringers, it will be noted that grooves 30 are provided between the bent ends of the locking members to accommodate the thumb and finger of the operator while closing the fastener. It will also be understood that if desired, a suitable slider may be provided for operating the fastener which may be of the type disclosed in my co-pending application above referred to.

In operation, assuming the fastener to be open, the operator simply places his thumb and finger in the grooves 30 and moves them along the fastener, taking care that the edges 25 of the stringer in advance of his thumb and finger, are well apart so that the locking members come together at an angle as indicated in Figure 4. Each of the interlocking tongues 18 passes through an aperture 19 on the opposite member and locks behind one 30 of the shoulders 21. One after another of the pairs of locking members are thus interlocked progressively and when the thumb and finger reach the end of the stringer, the 35 fastener is completely closed. Thereafter a pull on the edges of the material to which the fastener is attached will not open the fastener but intended opening may be very easily accomplished by simply beginning at 40 one end and tearing the fastener open.

As a result of my invention, it will be apparent that a novel construction of interlocking element has been provided especially adapted for that type of fastener where the 45 locking members are secured to the inner faces of overlapping flexible stringers, leaving no metal exposed when the fastener is closed. It will be readily seen that the locking member of my invention can be very 50 easily and cheaply manufactured out of sheet metal.

The feature of a smooth outer surface for slider operated fasteners is being claimed more broadly in my co-pending application 55 Serial No. 406,279, filed as a continuation in part of the above mentioned application Serial No. 137,018, now Patent No. 1,746,565.

While I have in this application specifically shown and described one preferred embodiment and a modification thereof which my invention may assume in practice, it is to be distinctly understood that this embodiment and modification are merely for the 60 purposes of illustration and that various

other forms may be devised within the scope of my invention as defined in the following claims.

What I claim as my invention is:—

1. A separable fastener comprising a pair 70 of overlapping flexible stringers, a series of locking members arranged on the inner face of each of said overlapping stringers, said locking members being made from substantially flat strips of metal the body portions 75 of which are substantially parallel to said inner faces, an interlocking projection on each of said members of one series extending out from the face of the stringer at an acute angle, and means on the other series of members to receive and interlock with said projections.

2. A separable fastener comprising a pair of overlapping flexible stringers having locking members arranged on their adjacent overlapping faces each of said members comprising a substantially flat strip of metal having a body portion parallel with said stringer and bent to provide means for connection to said stringer, and an interlocking projection 85 comprising a tongue stamped out of the body portion of said strip of metal and fitted into a recess cut out of the body portion on the opposite adjacent locking member.

3. A separable fastener comprising a pair 95 of overlapping flexible stringers having locking members arranged on their adjacent overlapping faces each member on one stringer being arranged directly opposite a like member on the opposite stringer and constituting therewith an interlocking pair, an interlocking tongue on each of said members projecting at an acute angle therefrom and longitudinally of said stringers, and means on each of said members to receive and interlock 100 with the tongue on the opposite member.

4. In a separable fastener, a pair of members of flexible material, cooperating fastener elements attached to the adjacent edges of said members, and a separate flexible covering strip attached to each of said members adjacent said fastener elements, said covering strip extending over and at all times lying closely against said fastener elements.

5. In a separable fastener, a pair of members of flexible material, cooperating metal fastener elements attached to and projecting from the longitudinal edges of said members, and a thin covering strip of flexible material attached to each of said members adjacent 110 said fastener elements, said covering strip extending over said metal elements and lying closely against said elements at all times to provide a continuous smooth outer surface.

In testimony whereof I affix my signature.

GIDEON SUNDBACK.
